UNITED STATES PATENT OFFICE

EARL F. OYSTER, OF CLEVELAND HEIGHTS, AND FRANCIS N. GILLILAND, OF SHAKER HEIGHTS, OHIO, ASSIGNEES TO THE OSBORN MANUFACTURING COMPANY, OF CLEVELAND, OHIO, A CORPORATION OF OHIO

MECHANISM FOR MAKING MOLDS

Application filed August 2, 1928. Serial No. 296,883.

The present invention relates, as indicated, to a method of and mechanism for making molds, and more particularly to a mold making machine including improved means for stripping patterns from molds. The primary object of the invention is to provide a machine of the character described which shall be relatively simple in construction, extremely efficient in operation, and relatively inexpensive to manufacture. Further objects of the invention will appear as the description proceeds. To the accomplishment of the foregoing and related ends, said invention, then, consists of the means hereinafter fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawings:

Fig. 1 is a side elevation of a machine incorporating the present invention, a portion thereof being broken away, substantially on the line 1—1 of Fig. 3, and looking in the direction of the arrows; Fig. 2 is a front elevation of said machine on a reduced scale; and Fig. 3 is a fragmentary sectional view taken substantially on the line 3—3 of Fig. 1.

Referring more particularly to the drawings, it will be seen that the machine comprises a C-shaped frame 10 including or mounting a base 11 formed with a substantially central chamber 12 in which are received a squeeze piston 13 and a jolt piston 14 nested in said squeeze piston. As will be obvious, the piston 13 is slideable in the chamber 12 while the piston 14 is also slideable within the piston 13. The piston 14 is formed or provided at its end with a platform 15 carrying a flask-receiving frame 16.

At each end, said base 11 is formed with a chamber 17, a portion 18 of which is cylindrical as shown, and an annular wall 19 forms a continuation of said cylindrical portion 18. Within each said cylindrical portion there is mounted a piston 20 carrying or formed with a pair of laterally projecting arms 21 and 22

at its upper end. As will be obvious, the arms 21 and 22 are carried outside of the cylindrical portion 18 but within the chamber 17. Said arm 21 is formed at its outer end with a relatively deep socket 23, and the arm 22 is formed with a similar socket 24. The upper open end of each chamber 17 is closed by a head member 25.

A pair of stripper rods 26 and 27 have their lower ends received in the sockets 23 and 24 respectively, and the head member 25 is formed with a pair of apertures 28 in alignment with said respective sockets. Each aperture 28 receives a bushing 29 through which the upper ends of the rods 26 and 27 slidably project. A stop member 30 is carried by said head member 25 intermediate the apertures 28 therein, and a similar stop member 31 is carried by said piston 20 at its upper end. Each of the rods 26 and 27 is provided adjacent its upper end with adjusting mechanism 32 whereby the exact position of the upper end 33 of each rod may be adjusted.

A control valve 34 provided with an operating handle 35 is connected by a pipe line 36 with a source of fluid under pressure and a pipe line 37 leads from said valve to a pair of branch pipes (not shown) communicating respectively with the chamber at the base of the piston 13 and the chamber within said piston 80 at the base of the piston 14, while a pipe line 38 leads from said valve to branches 39 and 40 opening respectively into the bases of the two cylindrical portions 18 of the chambers 17. As is clearly illustrated in Fig. 3, the branches 39 and 40 are connected with passages 41 formed in removable closures secured in place over the lower ends of the cylindrical portions 18 and of the chambers 17, said closures being formed with expansion 85 chambers 42.

The operation of the above described device is as follows. An empty flask 43 is set on the frame 16 and is filled with sand, it being understood that a pattern is resting on the platform 15 and projects into said flask. The valve 34 is operated to admit air or other fluid to the chamber at the base of the piston 14, and suitable mechanism is provided whereby the platform 15 is jolted or rapidly vi-

brated. Thereafter, the handle 35 of the valve 34 is set in a second position which causes the admission of fluid under pressure to the chamber at the base of the piston 13 to elevate the platform 15 until the sand in the 5 flask 43 is brought into contact with a suitable member carried by the head 44. With the handle 35 in this position, heavy pressure is applied to the piston 13, whereby the 10 sand in the flask 35 is squeezed between the platform 15 and the member carried by the head 44. In this position of the valve handle 35, fluid is also admitted to the two cylindrical portions 18 to cause elevation of the pistons 20. As will be obvious, said pistons, being 15 entirely independent of each other, may move upwardly at different rates, but the valve apertures are so proportioned that neither piston 20 may move as fast as does the piston 13, and that the stop members 31 of both pistons 20 will contact with the stop members 30 before the squeezing operation has been completed. Thus it will be seen that provision 20 has been made for bringing the upper ends 33 of both stripper units to a common level, even though the two units are entirely independent of each other. In some cases, it is found that the frame 16 becomes warped, and under such circumstances, the ends 33 of the stripper 25 rods 26 and 27 may be differently set by the adjusting means 32. In the appended claims, 30 the language "a common level" is to be interpreted to include such a setting. The valve handle 35 is now moved to a third position which causes release of the actuating fluid 35 from the chamber 12 to permit the platform 15 to move downwardly. As will be obvious, 40 the upper ends 33 of the stripper rods 26 and 27 are disposed in the path of the frame 16 which supports the flask, and consequently 45 said frame will come into contact with said ends and be stopped thereby during the downward movement of the platform 15, it being understood that this third position of the 50 valve handle 35 holds the pressure fluid in the cylinders 18. After the frame 16 comes into contact with the stripper rods, the platform 15 continues to descend, thus permitting the pattern to be drawn downwardly out of the flask 43.

Other modes of applying the principle of our invention may be employed instead of the one explained, change being made as regards the mechanism herein disclosed, provided the means stated by any of the following claims or the equivalent of such stated means be employed.

We therefore particularly point out and distinctly claim as our invention:

60 1. In a mold making machine, a base, a mold-carrying platform reciprocably mounted in said base, fluid actuated means for reciprocating said platform, a plurality of independent stripper units mounted in said base, and fluid actuated means for moving

said units into flask-receiving position and holding the same in such position.

2. In a mold making machine, a base, a mold-carrying platform reciprocably mounted in said base, stripper mechanism comprising a plurality of independent reciprocable units, means for elevating said units, and means for limiting the upward movement of said units to dispose their upper ends at a common level, said last-named means operating with said elevating means to hold said units in such position. 75

3. In a mold making machine, a base, a mold-carrying platform reciprocably mounted in said base, stripper mechanism comprising a plurality of independent reciprocable units, fluid-actuated means for elevating said units, and means for limiting the upward movement of said units, said last-named means cooperating with said fluid-actuated means to hold said units in position with the upper ends of said units at a common level. 80

4. In a mold making machine, a base, a mold-carrying platform reciprocably mounted in said base, and stripper mechanism comprising a plurality of independent reciprocable units, fluid actuated means for causing reciprocation of said units, and automatic means for causing the upper ends of said units to assume a common level at the upper 85 extremities of the strokes thereof. 90

5. In a mold making machine, a base, a mold-carrying platform reciprocably mounted in said base, and stripper mechanism comprising a plurality of independent reciprocable units, means for causing reciprocation of said units, and independent stop means for limiting the upward strokes of said units, respectively. 100

6. In a mold making machine, the combination of a base providing a chamber, a piston in said chamber and having a mold-carrying platform at its upper end, means for elevating said piston, and stripper mechanism comprising a pair of independent units, means for elevating said units, and means for stopping the upward movement of said units at a common upper level. 105

7. A mold making machine comprising a base formed with a chamber therein adjacent each end thereof, a piston mounted in each such chamber, a stripper rod carried by each of said pistons, and means for supplying fluid under pressure to each such chamber. 115

8. A mold making machine comprising a base formed with a chamber therein adjacent each end thereof, a piston mounted in each such chamber, a stripper rod carried by each of said pistons, means for supplying fluid under pressure to said chambers, and means mounted in said respective chambers and adapted to cooperate with said pistons to cause the upper ends of said rods to assume a common level at the extremities of their upward strokes. 125

9. A mold making machine comprising a base formed with a chamber therein adjacent each end thereof, a piston mounted in each such chamber, a stripper rod carried by each of said pistons, means for supplying fluid under pressure to said chambers, and separate means automatically cooperable with said respective pistons to cause the upper ends of said rods to assume a common level at the extremities of their upward strokes.
10. A mold making machine comprising a base formed with a chamber adjacent each end thereof, a portion of each of said chambers being cylindrical, a piston reciprocable in each of said cylindrical portions, a socketed arm carried by each of said pistons without said cylindrical portions, and a stripper rod mounted in the socket of each of said arms.
11. A mold making machine comprising a base formed with a chamber adjacent each end thereof, a portion of each of said chambers being cylindrical, a piston reciprocable in each of said cylindrical portions, a pair of socketed arms carried by each of said pistons without said cylindrical portions but within said chambers, and a stripper rod having its one end received in each of said arm sockets and its opposite end projecting out of its chamber.
12. A mold making machine comprising a base formed with a chamber adjacent each end thereof, a portion of each of said chambers being cylindrical, a piston reciprocable in each of said cylindrical portions, a pair of socketed arms carried by each of said pistons without said cylindrical portions but within said chambers, a stripper rod having its one end received in each of said arm sockets and its opposite end projecting out of its chamber, and means for supplying fluid under pressure to said respective cylindrical portions.
13. A mold making machine comprising a base formed with a chamber adjacent each end thereof, a portion of each of said chambers being cylindrical, independent pistons reciprocably mounted in said cylindrical portions, a pair of socketed arms carried by each of said pistons without said cylindrical portions but within said chambers, and a stripper rod having its one end received in each of said arm sockets and its opposite end projecting out of its chamber.

Signed by us this 31st day of July, 1928.
EARL F. OYSTER.
FRANCIS N. GILLILAND.
